UNITED STATES PATENT OFFICE.

JACOB M. MCQUILLAN, OF PITTSBURGH, PENNSYLVANIA, ASSIGNOR TO WINTERTON MANUFACTURING COMPANY, OF PITTSBURGH, PENNSYLVANIA, A CORPORATION OF PENNSYLVANIA.

DESIGN FOR A WIND-SHIELD FOR MOTOR-VEHICLES AND THE LIKE.

43,406.

Specification for Design.

Patented Dec. 31, 1912.

Application filed September 17, 1912. Serial No. 720,903. Term of patent 7 years.

To all whom it may concern:

Be it known that I, JACOB M. MCQUILLAN, a citizen of the United States, residing at Pittsburgh, in the county of Allegheny and State of Pennsylvania, have invented a new, original, and ornamental Design for Wind-Shields for Motor-Vehicles and the Like, of which the following is a specification, reference being had to the accompanying drawing, forming part thereof.

Figure 1 is a perspective view, and Fig. 2 is a side elevation, of a wind shield, showing my new design.

I claim:

The ornamental design for a wind shield as shown.

JACOB M. MCQUILLAN.

Witnesses:

W. L. WOODS,
E. S. THOMAS.
